UNITED STATES PATENT OFFICE.

HERMAN FREDERICKSON, OF MARINERS HARBOR, NEW YORK.

HEATING STOVE AND FURNACE.

1,144,117.

Specification of Letters Patent. Patented June 22, 1915.

Application filed February 25, 1915. Serial No. 10,440.

To all whom it may concern:

Be it known that I, HERMAN FREDERICKSON, a citizen of the United States, and residing at Mariners Harbor, Staten Island, in the county of Richmond and State of New York, have invented certain new and useful Improvements in Heating Stoves and Furnaces, of which the following is a specification, such as will enable those skilled in the art to which it appertains to make and use the same.

This invention relates to stoves and furnaces of the class used for heating rooms or compartments in a building, and the object thereof is to provide an improved device of this class which may be used for heating a room or compartment in which it is placed and also other rooms or compartments in the same building, and which is simple in construction, efficient in operation and may be easily cleaned or repaired whenever necessary, and with this and other objects in view the invention consists in a device of the class specified, constructed as hereinafter described and claimed.

The invention is fully disclosed in the following specification, of which the accompanying drawing forms a part, in which the separate parts of my improvement are designated by suitable reference characters in each of the views, and in which:—

Figure 1 is a central vertical section of a heating apparatus or device of the class specified, constructed according to my invention; and, Fig. 2 a front view thereof and showing a modification.

In the practice of my invention, as shown in the drawing, I provide a main outer casing *a* in which is placed a stove or furnace body *b* composed, in the construction shown, of top and bottom members *b*² and *b*³, and beneath the stove or furnace body *b* is the usual ash-pit *b*⁴ between which and the body *b* is a grate *c* of any preferred construction, and the ash-pit *b*⁴ is provided with a door *d* made, as shown, in the form of an air register device *d*² through which air may be admitted into the ash-pit from which it will pass up through the grate *c* into the body *b*.

The top part *b*² of the body *b* is provided at one side thereof with a tubular inlet or neck *b*⁵ through which coal or other fuel may be passed into the body *b*, and this inlet *b*⁵ connects with the casing *a* and is provided with a door *e* which is also preferably provided with an air register device *e*².

At the bottom of the casing *a* and on the opposite sides thereof are inlet air registers *f* of any suitable construction and by means of which air in any desired quantity may be admitted into the bottom of said casing, and at the bottom of said casing and preferably at the back thereof, I place a water tank *g* which may be detachably, or otherwise, secured in said casing, and which extends inwardly through said casing and the top portion of which is provided with ports or passages *g*² through which vapor may escape and mingle with the air passing upwardly through said casing, and that part of the water tank *g* outside of the casing *a* is provided with a door *g*³ through which said tank may be filled, or partially filled with water.

In the top part of the casing *a* and over the body *b* is placed a box member *h* which rests on the top part *b*² of the body *b*, and is secured thereto at *h*² in any desired manner, and the bottom of which is provided with a large aperture *h*³ through which the hot gases or products of combustion pass from the body *b* into the box member *h*, and at the front of the stove or furnace the box member *h* is provided with a tubular neck *h*⁴ which connects with the front of the casing *a* and is provided with a closure cap *h*⁵ which may be detached when necessary, and this forms an aperture through which the interior of the box member *h* may be cleaned whenever desired of any deposits which may collect therein.

The casing *a* is provided with a cap or cover *a*² provided centrally with an air flue *i* through which hot air is, or may be conveyed, upwardly from the stove or furnace into compartments arranged over that in which the stove or furnace is located, and the box member *h* is provided with an elbow pipe or flue *j* which connects with the central top portion of said box member and passes out through one side of the air flue *i*, and through which the smoke and other hot gases of combustion pass, but my invention is not limited to the shape of the flue *j*, and said flue may be extended vertically through the air flue *i*, if desired, and as indicated in dotted lines at *j*². The box member *h* is also provided at the back of the stove with a neck-shaped flue extension *k* which connects with the casing *a* and is provided with a detachable cap *k*², and the escape flue *j*, or an escape flue of any form

and construction may be connected with the flue extension *k* instead of with the top of the box member *h* as shown. With this construction the air enters the casing *a* at the bottom thereof and passes up around the stove body *b* and around the box member *h* and out through the air flue *i*, as indicated by the arrows *x*, and the products of combustion pass from the body *b* through the box member *h* and through the flue *j*, as indicated by the arrows *x²*, and the air is highly heated and may be used for heating rooms or compartments other than that in which the stove or furnace is placed and any part of a building, and the casing *a* radiates ample heat for heating the room or compartment in which the said stove or furnace is placed.

The box member *h* is preferably provided with a horizontal partition plate *m* which extends from one end thereof longitudinally thereof, to within a predetermined distance from the other end and which is provided with an upwardly directed extension *m²*, and the hot products of combustion in their passage through said box member pass around the plate *m*, and the part *m²* thereof, as indicated, and this forms a tortuous passage for said products of combustion, whereby the greatest amount of heat units are utilized, but my invention is not limited to any particular construction, or means for forming a tortuous passage through the box member *h*. When it is desired to use the stove or furnace for the purpose of heating only the compartment or room in which said stove or furnace is placed the air flue *i* and smoke flue *j* may be detached, and a cap *n* may be substituted for the air flue *i*, as shown in Fig. 2, and the smoke flue may be connected with the back of the stove at *k*, as herein-

before described, and while I have shown and described the construction which I prefer in carrying my invention into effect, my invention is not limited to the details of construction herein shown and described, and changes therein and modifications thereof, may be made, within the scope of the appended claim, without departing from the spirit of my invention or sacrificing its advantages.

Having fully described my invention, what I claim as new and desire to secure by Letters Patent, is:—

A heating apparatus of the class described, comprising a stove or furnace body, a casing inclosing said body and provided at the bottom thereof with air inlets, and a box member placed on the top of the stove or furnace body and inclosed by said casing and around which air admitted at the bottom of said casing passes, said box member being in communication with the stove or furnace body and being provided with a tortuous passage for the products of combustion, and centrally of the top thereof with an attachment for a smoke flue, the top of the casing being also provided with an attachment for an air flue, and said box member being provided at one side with a doorway which opens through the corresponding side of the casing and at the opposite side with a smoke flue attachment which opens through said side of the casing.

In testimony that I claim the foregoing as my invention I have signed my name in presence of the subscribing witnesses this 23rd day of February 1915.

HERMAN FREDERICKSON.
